UNITED STATES PATENT OFFICE.

AUGUSTUS M. SAUNDERS, OF MCKEESPORT, PENNSYLVANIA, ASSIGNOR TO NATIONAL TUBE COMPANY, OF PITTSBURG, PENNSYLVANIA, A CORPORATION OF NEW JERSEY.

PLATE-BENDING APPARATUS.

965,018.

Specification of Letters Patent. Patented July 19, 1910.

Application filed December 8, 1909. Serial No. 531,965.

To all whom it may concern:

Be it known that I, AUGUSTUS M. SAUNDERS, of McKeesport, Allegheny county, and State of Pennsylvania, have invented a new

5 and useful Improvement in Plate-Bending Apparatus, of which the following is a full, clear, and exact description, reference being had to the accompanying drawings, forming part of this specification, in which—

10 Figure 1 is a longitudinal side elevation showing the overhead traveling ram as constructed and applied for use in connection with power bending rolls in accordance with my invention. Fig. 2 is a sectional end elevation of the same on the line II—II of Fig. 1.

15 My invention relates to apparatus used in connection with power bending rolls for bending metal plates into cylindrical form 20 which are afterward reheated and welded in being made into pipes or tubes. Heretofore with the apparatus used in bending such plates, after the plates have been bent by means of the bending rolls, the adjacent 25 longitudinal edges of the plates at the ends of the curved plates must be hammered into proper shape with sledges by manual labor, which is a slow and expensive operation.

20 The object of this invention is to provide 30 improved means by which such plates are given a cylindrical form and the edges of the bent plate are made of uniform and with a proper amount of lap along the entire length of the bent plate.

35 In the drawings 2—2 represent the two bottom and 3 the top roll of a set of power bending rolls, mounted in suitable bearings on the shoes 4 and driven through the spur gears 5 by means of any suitable type of 40 motor which is operatively connected to the driving shaft 6.

45 Located above the bending rolls 2, 3 and extending lengthwise of these rolls is a runway track formed by the girders 7 which are secured to the columns 7' of the runway structure and mounted upon the track formed by the girders 7 is a traveling ram forming part of my invention which is arranged to travel lengthwise from end to end 50 of the track girders. The ram as shown consists of two parallel rollers 8 mounted in bearings 9 secured on the ends of the cross-head 10, and connected by one end to this cross-head is a piston rod 11 having on its 55 opposite end a piston which is operatively

mounted in the fluid pressure cylinder 12, so as to move the cross-head 10 and rollers 8 vertically relative to the power bending rolls.

60 The fluid pressure cylinder 12 is provided with wings 13 forming supports which project into the recessed slides on the track girders so as to permit of longitudinal movement of the ram while preventing its being lifted from its track when being used to reinforce and prevent springing of the top bending roll 3 at the beginning of the plate bending operation, or in bending the longitudinal edges of the plate into engagement in completing the plate bending operations. The cross-head 10 is also provided 65 with guide rods 14 which operate through suitable guides forming part of the cylinder 12 and cushioning means formed by springs 15 on the rods 16 are provided to lessen the 70 shock of the upward stroke of the cross-head when being lifted in operating the apparatus.

75 The cylinder 12 of the traveling ram is connected by means of a flexible connection 80 17 with the slow down gearing 18 to a driving motor 19 by which the ram is caused to travel lengthwise on its ways in bringing the ram in engagement with the entire length of the plate being bent. As shown in the 85 drawings, one end of the connection 17 is attached to one side of the cylinder 12 and after passing around the sheave wheel 20 and the idler sheave wheel 21 on the opposite end of the runway, has its other end connected to the opposite side of the cylinder 12. The cylinder 12 is double acting and 90 fluid pressure is supplied to one end through walking pipes 22 which are connected by the pipe 23 with a suitable source of fluid pressure, the opposite end of the cylinder 12 also being connected by the pipe 24 and walking pipes 25 with a source of fluid pressure supply.

95 In the operation of my improved apparatus, 100 the plate to be bent into cylindrical form is heated to the proper temperature and is then placed between the power bending rolls from one side at the proper angle. The ram which is preferably in the position upon the 105 runway shown in full lines in Fig. 1 is then lowered by means of the fluid pressure cylinder 12, until the rollers 8 are in engagement with the bending roll 3 so as to form a support for and prevent springing of this roll 110

3 during the plate forming operation. As soon as the plate has passed through the rolls 22 and 23 sufficiently to come into proximity to or strike the rollers 8 or the side of 5 the cross-head 10, the ram is lifted by means of the power cylinder 12 until the rollers 8 are above the plate being bent. The bending rolls are then rotated and the plate is 10 passed farther between the bending rolls and the ram is again caused to descend until the rollers 8 are in contact with the outer surface of the plate being bent, when the rotation of the bending rolls and necessarily the plate is continued. This operation causes 15 one edge of the plate to be forced downwardly into engagement with the adjacent longitudinal edge of the plate as shown at A in Fig. 1. The plate is then caused to rotate backwardly and forwardly between the 20 bending rolls, this operation giving the plate a substantially cylindrical form opposite the rollers 8. The traveling ram after being raised is then moved longitudinally or in the direction of the axes of the bending rolls 25 and is again caused to descend. The rolls are then rotated until the rollers 8 have pressed the high edge portions B and, in other similar operations the high edge portion C is pressed downwardly until in engagement with the opposite longitudinal 30 edge portion of the plate being bent. The plate is also moved backwardly and forwardly between the bending rolls by rotating these rolls and is caused to assume a cylindrical form opposite the high points B and C. In this way the bent plate is formed to the desired curvature throughout its entire length and the lap is made uniform throughout its length. This is of particular 35 value in making the larger sizes of pipes and in making extra length pipes. The bent plate is then removed endwise from the bending rolls when the apparatus is in readiness to again perform the bending operations 40 as described.

The advantages of my invention are many and will be appreciated by those skilled in the art.

By its use the plates are bent to the desired 50 curvature and the opposite longitudinal edges of the plates are brought into the desired close contact and with the desired amount of lap without difficulty, and the number of defective pipes or tubes made in the later welding operations is thereby 55 greatly reduced. The ram is adapted to operate all points in the length of the pipes being used and in engaging with the top bending roll 3 during the beginning of the 60 plate bending operation reinforces and prevents any spring in the top bending roll and greatly increases the efficiency of the bending rolls. The apparatus is simple and is easily kept in repair.

65 Modifications in the construction and ar-

rangement of the parts may be made without departing from my invention. The plates may be heated or not as is desired. The means employed for actuating the ram on its track as well as into and out of its 70 operative position may be modified and other changes may be made.

I claim:

1. Apparatus for bending metal plates, comprising bending rolls, a ram movable toward and away from said rolls, a carrier on which the ram is movably mounted, a track for the carrier, and means for moving the carrier on said track; substantially as described. 75

2. Apparatus for bending metal plates, comprising bending rolls, an overhead ram movable toward and away from said rolls, a carrier on which said ram is mounted, a track for the carrier, and means for moving the carrier on said track; substantially as described. 80

3. Apparatus for bending metal plates, comprising bending rolls, a carrier having a movable ram mounted thereon adapted to 90 engage with and bend the marginal side edges of the plates held between said rolls, a track for said carrier, and means for moving the carrier on the track; substantially as described. 95

4. Apparatus for bending metal plates, comprising bending rolls, an overhead carrier having a vertically movable ram mounted thereon adapted to engage with and bend the marginal side edges of the plates held between said rolls, a track for said carrier, and means for moving the carrier on said track; substantially as described. 100

5. Apparatus for bending metal plates, comprising plate bending rolls, an overhead 105 carrier having a vertically movable plate bending ram mounted thereon, means for moving said ram on the carrier into engagement with a plate held between the rolls, a track for the carrier, and means for moving the carrier on said track; substantially as described. 110

6. In apparatus for bending metal plates, the combination with bending rolls of an overhead track extending lengthwise of said 115 rolls, a carrier on said track, a vertically movable plate bending ram on the carrier, means for moving the carrier on the track, and means for moving the ram on the carrier into engagement with a plate held between the rolls; substantially as described. 120

7. In apparatus for bending metal plates, the combination with bending rolls of a track extending lengthwise of said rolls, a carrier on the track, a ram movable toward and away from the rolls mounted on said carrier, means for moving the ram on the carrier, and means for moving the carrier on the track; substantially as described. 125

8. Apparatus for bending plates, compris- 130

- ing bending rolls, an overhead track above said bending rolls, a fluid pressure cylinder movably mounted on said track, means for moving said cylinder on the track, and a 5 vertically movable ram operatively connected to said cylinder and arranged to move toward and away from said bending rolls; substantially as described.
9. Apparatus for bending metal plates 10 comprising bending rolls, a ram above said rolls, means for moving the ram toward and away from the rolls and means for moving said ram in the direction of the length of said rolls; substantially as described.
- 15 10. Apparatus for bending metal plates comprising bending rolls, a movable ram above said rolls, a carrier for the ram and means for moving the carrier and ram in the direction of the length of said rolls; sub- 20 stantially as described.
11. Apparatus for bending metal plates comprising bending rolls, a ram, means for moving the ram lengthwise of said rolls, and means for moving said ram into and out of engagement with plates being bent by the 25 rolls in different positions relative to the length of said rolls; substantially as de- scribed.
12. Apparatus for bending metal plates comprising bending rolls, a ram movable 30 toward and away from said rolls, means for moving said ram lengthwise of the rolls, and means for moving said ram into and out of engagement with plates being bent by the rolls, said ram having a plurality of anti- friction rollers mounted thereon and adapt- ed to contact with the plates being bent; 35 substantially as described.

In testimony whereof, I have hereunto set my hand.

AUGUSTUS M. SAUNDERS.
